UNITED STATES PATENT OFFICE

142,459

DESIGN FOR A LAY FIGURE

Albert L. Westerman, Delaware County, Pa., assignor to American Viscose Corporation, Wilmington, Del., a corporation of Delaware

Application February 6, 1945, Serial No. 117,792

Term of patent 14 years

(Cl. D1—2)

To all whom it may concern:

Be it known that I, Albert L. Westerman, a citizen of the United States, residing at Delaware County, Commonwealth of Pennsylvania, have invented a new, original, and ornamental Design for a Lay Figure, of which the following is a specification, reference being had to the accompanying drawing, forming part thereof.

I claim:

The ornamental design for a lay figure, as shown.

ALBERT L. WESTERMAN.
